[57] CLAIM

The ornamental design for a combined transmitter for children monitoring and base therefor, as shown and described.

DESCRIPTION

FIG. 1 is a perspective view of the combined transmitter for children monitoring and base therefor;

FIG. 2 is a front elevation view thereof;

FIG. 3 is a right side elevation view thereof;

FIG. 4 is a left side elevation view thereof;

FIG. 5 is a rear elevation view thereof;

FIG. 6 is a top plan view thereof;

FIG. 7 is a bottom plan view thereof;

FIG. 8 is a perspective view of the transmitter portion, shown separate for clarity of illustration only;

FIG. 9 is a front elevation view thereof;

FIG. 10 is a right side view thereof;

FIG. 11 is a left side view thereof;

FIG. 12 is a rear elevation view thereof;

FIG. 13 is a top plan view thereof;

FIG. 14 is a bottom plan view thereof;

FIG. 15 is a perspective view of the base portion, shown separate for clarity of illustration only;

FIG. 16 is a front elevation view thereof;

FIG. 17 is a right side view thereof, the left side view being a mirror image thereof;

FIG. 18 is a rear elevation view thereof;

FIG. 19 is a top plan view thereof; and,

FIG. 20 is a bottom plan view thereof.
